UNITED STATES PATENT OFFICE

CURT WOLFELT, OF NEW YORK, N. Y., ASSIGNOR TO ANDREW GELLER SHOE MANUFACTURING CO. INC., OF BROOKLYN, NEW YORK, A CORPORATION OF NEW YORK

DESIGN FOR A SHOE

Application filed January 2, 1931. Serial No. 38,172. Term of patent 3½ years.

To all whom it may concern:

Be it known that I, CURT WOLFELT, a citizen of the United States, and a resident of New York city, county and State of New York, have invented a new, original, and ornamental Design for Shoes, of which the following is a specification, reference being had to the accompanying drawings, forming a part thereof.

Fig. 1 is a perspective view of the left side of a shoe, showing my new design; and Fig. 2 is a perspective view of the opposite side of the shoe.

I claim:
The ornamental design for a shoe as shown.
Dated, December 31, 1930.

CURT WOLFELT.
